W. P. UHLINGER, OF PHILADELPHIA, PENNSYLVANIA.

Design No. 3,297, dated December 22, 1868.

DESIGN FOR A SCHOOL-DESK.

The Schedule referred to in these Letters Patent and making part of the same.

To all whom it may concern:

Be it known that I, W. P. UHLINGER, of the city and county of Philadelphia, in the State of Pennsylvania, have originated and designed a new Form for School-Desks, of which the following is a full, clear, and exact description, reference being had to the accompanying drawings, making a part of this specification.

Figure 1 of the drawings is a representation of my school-desk, and

Figure 2 is the same desk, with the seat thereof turned up and secured.

What I claim as my invention, and desire to secure by Letters Patent, is—

The design for school-desks, herein set forth and shown.

W. P. UHLINGER.
